RAILROAD TIE PLATE AND SPIKE

Oscar F. Arthur and Frederick Schulle,
Pueblo, Colo.

Application October 14, 1938, Serial No. 235,050

1 Claim. (Cl. 238—309)

Taking a 112 pound railroad rail as an example, the standard base of such a rail is five and one-half inches wide, but the rolling mills are permitted to increase this width up to one-sixteenth of an inch, this variation being known as tolerance. The mills, furthermore, are permitted to reduce the width of the rail base to a minimum of five and seven-sixteenths inches. The tie plate seat has a width, between the shoulders, of five and nine-sixteenths inches, with one-sixteenth of an inch additional tolerance permitted. The spike hole or slot through the tie plate, for five-eighths of an inch spikes, is eleven-sixteenths of an inch, and the mills are permitted a variation of one thirty-second of an inch in size and location. These combinations of tolerances in the plate seat, the rail and spike holes, therefore, allow a total tolerance of three-sixteenths of an inch on one rail, or three-eighths of an inch on both rails. This, naturally, sets up objectionable variations in the distance or gage between the rails.

In addition to inaccuracies of gage, due to the combination of tolerances above referred to, the low shoulder on tie plates now in use does not properly support the back of a spike. Therefore, the load thrust against the spike causes it to bend backwardly. Furthermore, the permissible tolerance in the spike hole, which makes it larger than the spike, permits the spike to be driven at an angle and allows the spike to twist out of position while being driven. These inaccuracies in spike driving have become more pronounced since the recent method of using power hammers has been placed generally in effect.

The purpose of the present invention is to get away from the variations or tolerances in the spike holes through the tie plate, to provide a spike hole or slot that will not permit the spike to be driven at an angle or twist, and to provide a high backup shoulder supporting the spike and preventing it from bending outwardly under load thrusts. In order to accomplish this end, the spike hole and the spike have been so made that when the spike is driven into the slot, it will be perfectly seated, having contact with the plate on all four sides, and since the slot in the plate fits the spike, the spike, during driving, will be guided to proper position and will not twist out of place.

It is within the province of the disclosure to improve generally and to enhance the utility of devices of that type to which the present invention appertains.

With the above and other objects in view,

which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in elevation, a device constructed in accordance with the invention, the rail being in section;

Fig. 2 is a section on the line 2—2 of Fig. 1;

Fig. 3 is a top plan of the spike; and

Fig. 4 is a section at right angles to the showing of Fig. 2.

In the drawing there is shown a tie 1, on which rests a tie plate 2. The tie plate 2 is supplied with upstanding shoulders 3 of considerable height, and of considerable width transversely of the tie plate 2. Between the shoulders 3 there is a seat 4, receiving the flange 5 of a rail 6.

Any desired number of openings 7 are formed in the tie plate 2, through the shoulders 3, and nearer to the inner edges of the shoulders than to the outer end surfaces thereof. The openings 7 are of polygonal cross section, preferably square, and they taper, as they extend downwardly.

A spike is shown at 8 and includes a neck 9 and a head 10. The neck 9 of the spike is of polygonal cross section, preferably square, and, when the spike is driven, the neck 9, in cross section, will conform closely to the cross section of the opening 7, the neck of the spike being seated firmly in the opening.

Owing to the high backup shoulders 3 that are provided, the spike 8 cannot bend backwardly under thrust, nor can it twist more or less out of place, about a substantially vertical axis.

The cross section of the neck 9 of the spike 8 is such, considered relatively to the cross sectional area of the opening 7, that, when the neck of the spike is seated firmly in the opening, the head 10 of the spike will bear downwardly upon the upper surface of the flange 5 of the rail 6, the neck 9 of the spike being spaced from the edge of the flange 5, and the rail 6 being held in place by downward pressure on the upper surface of the flange 5.

The inner wall of the opening 7 is vertical, the head 10 of the spike bearing on the upper surface of the flange 5 of the rail, but there being no engagement between the neck 7 of the spike and the edge of the flange 5 of the rail.

The device is so constructed that it will take care of variations in gage, due to tolerance. The spike will be prevented from twisting as it is driven, and the spike will arrive at a firm seat in the spike hole. Moreover, the spike is restrained against outward bending, due to the provision of the high backup shoulder 3.

Having thus described the invention, what is claimed is:

- 10 In a device of the class described, a tie plate having an upstanding shoulder, there being a downwardly tapered opening in the plate and

the shoulder, the inner wall of the opening being disposed at right angles to the lower surface of the plate, and a spike having a head and a downwardly tapered neck, the neck being shaped to seat firmly in the opening before the under-surface of the head is flush with the upper surface of the shoulder, the inner surface of the neck being parallel to the longitudinal axis of the spike, for cooperation with the inner wall of the opening.
